Inventor,
Donald Codd, by
Benj. Butterworth,
his Attorney.

UNITED STATES PATENT OFFICE.

DONALD CODD, OF WINNIPEG, MANITOBA, CANADA, ASSIGNOR TO ROBERT D. RICHARDSON, OF SAME PLACE.

PENCIL-SHARPENER.

SPECIFICATION forming part of Letters Patent No. 399,839, dated March 19, 1889.

Application filed June 22, 1888. Serial No. 277,896. (No model.)

To all whom it may concern:

Be it known that I, DONALD CODD, a citizen of Great Britain, residing at Winnipeg, in the county of Selkirk and Province of Manitoba, Canada, have invented certain new and useful Improvements in Pencil-Sharpener; and I do hereby declare the following to be a full, clear, and exact description of the invention, such as will enable others skilled in the art to which it appertains to make and use the same.

My invention consists in a pencil-sharpener for slate-pencils which will not lose its cutting-edge, will not readily clog up or break the pencil-point, and the combination of the same with an eraser.

In the drawings, Figure 1 is a perspective view of my pencil-sharpener and eraser. Fig. 2 is a cross-section of the same. Fig. 3 is a vertical longitudinal section of the same.

A is the frame, which is preferably cast of pewter or other suitable metal. In the frame A are set the saw-blades B, C, D, and E. The lines of teeth on these saw-blades, as G II and M H, Fig. 3, converge and meet in the same point H. Any suitable eraser, F, is attached to the frame A in any convenient manner.

It is evident that when the end of a pencil is inserted in that end of the sharpener at which the saw-blades are farthest removed one from the other and revolved the saw-teeth will cut the end of the pencil until, as it is pushed farther into the sharpener, it will be reduced to a long conical point. The teeth of the various saw-blades will not follow in one another's paths; but as the pencil is gradually driven down each will cut a separate path for itself of inconsiderable depth,

and therefore the point produced will have a nearly smooth surface and will not be composed of a series of prominent ridges.

A second advantage is that the saw-teeth hold their cutting-edge, since the entire width of the blade furnishes a backing for the narrow apex of the tooth, which does the cutting.

Another advantage is that the material falls between the saw-blades and does not pack. Consequently it can easily be removed by blowing in the sharpener, or in most cases will drop out of itself.

It is too evident to need illustration that three or five or any greater number of saw-blades might be used; but I have shown four as being the most natural and convenient arrangement.

Having therefore described my invention, both in essence and detail, what I claim as new, and desire to protect by Letters Patent, is—

1. A pencil-sharpener the cutting-edges of which consist of several separate and distinct series of saw-teeth, the lines of which teeth converge, substantially as described.

2. A pencil-sharpener which has, in combination, the frame and the saw-blades set in the frame, the lines of the teeth on which saw-blades converge, substantially as described.

3. A pencil-sharpener and eraser which has, in combination, the frame and eraser attached to the frame, and the saw-blades set in the frame, substantially as described.

In testimony whereof I affix my signature in presence of two witnesses.

DONALD CODD.
